By

Attorney

UNITED STATES PATENT OFFICE.

EDWIN J. FAGER, JR., OF HARRISBURG, PENNSYLVANIA.

WOODWORKING MACHINE.

Application filed February 13, 1922. Serial No. 536,336.

To all whom it may concern:

Be it known that I, EDWIN J. FAGER, Jr., a citizen of the United States, residing at Harrisburg, in the county of Dauphin and 5 State of Pennsylvania, have invented certain new and useful Improvements in Woodworking Machines; and I hereby declare that the following is a full, clear, and exact description thereof, reference being 10 had to the accompanying drawings, which form part of the specification.

This invention relates to improvements in woodworking machines, the specification and drawings of which are similar to my 15 pending application Serial Number 497, 914 filed September 2, 1921 with the exception of a slight change in the mounting of the carriage 25 upon the rods 22.

An object of this invention is to provide 20 a mitering machine having a traveling saw mounted on a rod sliding in a rotatable post, thus mitering at one angle, and angularly adjustable on the end of said rod to cut a miter in a different plane.

25 Referring to the drawings; Fig. 1, is a side elevation of a machine embodying my invention. Fig. 2, is a vertical cross section on the line 2—2 of Fig. 1. Fig. 3, is a top plan view of a portion of the machine.

30 Fig. 4, is a front view of the cross-head and mandrel. Fig. 5, is an end elevation partly in section of a portion of the carriage and one track.

35 Referring more particularly to the drawings; my invention consists in a table casting 10, having legs 11 and a table top 12 upon which is located a raised portion which I shall term the column base 13, this supports a column 14 with an overhanging 40 arm 15, which I will hereafter refer to as rotatable post 14.

The column base 13 and the rotatable post 14 have bored therein a vertical hole for the reception of a hollow pipe 16 which is 45 securely babbitted in the rotatable post and held in rigid relation thereto by set screws 17. The lower end of this hollow pipe 16 enters the column base 13 and is there surrounded by Babbitt metal, revolving there- 50 in like the pintle of a hinge.

A lateral screw 18 passes through the column base 13 and there attaches to a brake shoe 19 which engages the hollow pipe 16 thus providing a locking means to hold the 55 rotatable post 14 in any desired rotary position.

The column 14 is provided at its top with two oppositely disposed lateral extensions 20 and the above mentioned overhanging arm 15 is provided at its outer end with 60 two corresponding extensions 21.

On these extensions 20 and 21 are rigidly mounted two rods 22 which serve as tracks. These rods are held in place by screws 23, this being a convenient form of attachment. 65 Upon these rods is mounted by means of two wheels 24, a carriage 25, upon this carriage is slidably and adjustably secured a frame 26, supporting a motor 27 with a driving pulley 28. To the carriage 25 is 70 rigidly secured a sliding rod 29 which is above and parallel with the track rods 22. This sliding rod 29 passes through a bore 30 provided in the top of the rotatable post 14, positioned directly over the center of 75 the hollow pipe 16. An adjustable screw 31 passes through the top of the rotatable post 14 and secures the sliding rod 29 in a fixed position when so desired. To the other extremity of the sliding rod 29 is rigidly secured a collar 32. Another collar 33 is loosely mounted upon rod 29 and adjacent to collar 32 and connected thereto in rotary adjustment by bolts 34. This collar 33 is 80 integral with a cross head 35 through which 85 passes a saw mandrel 36, with a pulley 37 at the far end of said mandrel for belt connection to motor pulley 28.

The cross head 35 is adjustably connected as explained above by means of screws or 90 bolts 34 to the fixed collar 32, this permits of adjusting the cross-cut saw 38 in any slanting position desired. A handle 39 is attached to the cross head 35 for pulling the cross-cut saw through the work. 95

The table casting 10, may be provided with any suitable work supporting means, not shown.

To lock the rotatable post 14 in any desired position the screw 18 is tightened, thus 100 forcing the brake shoe 19 against the hollow pipe 16, thus rigidly holding said post.

Claims:

1. In a woodworking machine, the combination of a base frame, a rotatable post 105 mounted on said frame; a track mounted on said post; a carriage slidably mounted on said track; a rod attached to said carriage and slidable through said post; and a tool-carrying cross-head mounted on said 110 rod.

2. In a woodworking machine, the combi-

nation of a base frame; a rotatable post mounted on said frame; a track mounted on said post; a carriage slidably mounted on said track; a rod attached to said carriage and slidably through said post; a tool-carrying cross-head mounted on said rod and means for adjusting said cross-head relatively to said rod.

3. In a woodworking machine, the combination of a base frame; a rotatable post mounted on said frame; a track mounted on said post; a carriage slidably mounted on said track; a rod attached to said carriage and slidably through said post; a collar fixedly mounted on said rod; a second collar rotatably mounted on said rod; means

adapted to adjustably connect said collars; and a tool-carrying cross-head mounted on said second collar.

4. In a woodworking machine, the combination of a base frame; a rotatable post mounted on said frame and provided with a transverse bore and lateral extensions; two parallel rods fixed upon said extensions; a carriage mounted on said rods and adapted to travel thereon; a rod attached to said carriage and adapted to pass through said bore; and means mounted on said rod adapted to carry a woodworking tool.

In testimony that I claim the foregoing as my own, I affix my signature.

EDWIN J. FAGER, JR.
